UNITED STATES PATENT OFFICE.

WILLIAM C. ANDERSON, OF SAN JOSE, CALIFORNIA, ASSIGNOR TO ANDERSON-BARNGROVER MFG. CO., OF SAN JOSE, CALIFORNIA, A CORPORATION OF CALIFORNIA.

EVAPORATING APPARATUS.

SPECIFICATION forming part of Letters Patent No. 737,812, dated September 1, 1903.

Application filed January 20, 1903. Serial No. 139,757. (No model.)

To all whom it may concern:

Be it known that I, WILLIAM C. ANDERSON, a citizen of the United States, residing at San Jose, county of Santa Clara, State of California, have invented an Improvement in Evaporating Apparatus; and I hereby declare the following to be a full, clear, and exact description of the same.

My invention relates to an apparatus which is designed for evaporating, and is especially applicable to the evaporation of fruits of all kinds.

It consists in the construction of a furnace and drying-tunnels disposed in independent longitudinal channels, each adapted to receive a line of drying-trays, and in a means for regulating the application of heat, so that an approximately even division of the heat may be made and constantly directed through each of the drying-tunnels.

Referring to the accompanying drawings, Figure 1 is a vertical longitudinal section of the apparatus. Fig. 2 is an end view and partial transverse section of same. Fig. 3 is a detail in perspective, partially broken away, of the draft-chimney, showing the divisions thereof and the doors or dampers 15.

In the drying of fruit many different forms of apparatus have been devised, and traveling cars or carriers for trays and chambers in which the trays have been placed and moved from one end to the other are well known. A serious difficulty with drying chambers or tunnels where trays are placed in series or side by side is the difficulty in properly directing and controlling the heat, and this often causes the heat to be arrested in one portion of the apparatus and remain comparatively dead, so that the moisture evaporated from the fruit nearest the fire will be cooled, condensed, and deposited in the upper part of the tunnel, and the drying is arrested, so that the fruit will not be properly dried and in danger of subsequent spoiling.

It is the object of my invention to so construct an apparatus that I am enabled to keep up a constant current of hot air through a series of independent inclined tunnels, in which the fruit-trays are gradually moved from the most distant end toward the source

of heat, where they are eventually removed after the drying is finished.

As shown in the accompanying drawings, A is a casing of such length that it will receive a plurality of drying-trays, such as are ordinarily used for field-drying.

The tunnel is here shown as rectangular in shape, and it has vertical partitions 2 extending lengthwise from one end to the other. These partitions have longitudinal cleats projecting into the tunnel, so that the trays may rest upon these cleats. The usual construction is such as to allow each tunnel to receive a series of, say, ten trays in height, superposed one above the other and with sufficient space between them to allow the heated air from the furnace to be passed through them. These spaces increase in height from the top downward, so that the hot air rising to the top will enter the smallest passages and the cooler air nearer the bottom will find larger passages. The tunnel may be of any suitable or desired length. I have found that a very suitable length is enough to receive three trays eight feet in length, making about twenty-four feet for the whole length in addition to the hot-air inlet-space at the lower end. The tunnel is inclined, as shown in the drawings, sufficiently so that the loaded trays can be easily introduced at the upper end and pushed along by hand as the drying progresses. For convenience a suitable room, as at 4, serves for the introduction of the trays at the upper ends of the tunnels, and hinged-doors, as 5, close these ends after the trays have been introduced. These doors are preferably hinged in series, one above another, and each door controls a certain number of trays, which allows the remainder to continue in operation while one set is temporarily opened. At the discharge end is a stack or draft-chimney 6, connecting with the top and upper end of the tunnels, so that a draft is maintained from each tunnel through the stack independent of the others. At the lower end of the tunnels are hinged doors 5^a, also disposed in series, so that the trays can be removed from time to time into a suitable receiving-room after the drying has been completed, and only the compartment to be dis-

charged is opened, the others continuing at work.

The furnace structure may be made of brick or other suitable material and it is located beneath the lower end of the drying-tunnels, extending entirely across from one side to the other.

The joists or roof of the tunnels have sufficient openings between them at the lower end to allow the heat to rise into the tunnels, and passing up through them, it enters the draft-chimney compartments, and thus produces independent currents in each. Each of the tunnels is sufficiently narrow to insure a volume of heated air being passed through them. Regulating doors or dampers control the passage of the heat through either of the tunnels independently of the others. The trays are so disposed within the tunnels that the smallest passages for heat open above the uppermost trays, and the passages increase in size progressively downward, being largest at the bottom, as shown. This prevents the larger volume of heated air from rising to the top and equalizes the flow through all the series of trays from bottom to top.

The heaters 8 may be of any suitable or desired construction. I have here shown them in the form of independent stoves, so placed that fuel may be introduced through doors in the brickwork of the separate inclosing chambers, as at 9, and the heating-drums 10 are here shown surmounting the primary heaters, so that a large volume of heat may be radiated into the chambers and caused to pass thence up into the tunnels.

16 are deflectors fixed in the upper part of the heating-chambers and acting to direct the heat rearwardly through the slits or openings 40 into the rear of the tray-channels above. The radiators 10 are all connected with a draft pipe or flue 11, which extends transversely across the full width occupied by the parallel series of tunnels. Air is admitted into the 45 heating-chambers through inlet-openings made in the front and lower part of the front. There are as many of these heat-radiators as there may be tunnels, so that an apparatus comprises a series of independent parallel 50 tunnels and corresponding independent heating-apparatus, all connected with a single escape-flue, as herein shown. I am enabled in this manner to control the distribution of the heated air and to prevent any checking in any 55 one of the tunnel compartments, and I thus insure a more perfect evaporation than has heretofore been accomplished.

The top of the air draft-flue is provided with centrally-hinged doors, which may be 60 partially or wholly closed in stormy weather, leaving side openings for the escape of heat, and these doors may be fully opened in good weather to leave a free uninterrupted draft.

Having thus described my invention, what 65 I claim, and desire to secure by Letters Patent, is—

1. The combination in an evaporator of a

main casing having longitudinal vertical partitions by which it is subdivided into a series of parallel tunnels; inclined parallel cleats extending lengthwise of said tunnels and separated from each other to form spaces which increase in height from the top downward; a plurality of superposed trays mounted upon said cleats; a heating-chamber having vertical subdivisions corresponding with those of the tunnels; heaters located in said chambers; a draft-chimney correspondingly subdivided and connected with the upper end of the tunnels; and an independent damper for each subdivision of the chimney.

2. The combination in an evaporator of an inclined casing having vertical longitudinal partitions dividing it into a plurality of tunnels, parallel longitudinal cleats, a series of trays in each tunnel, slideable upon the cleats and separated by spaces which gradually increase from the top downward, and with corresponding increasing heat-admission openings, doors by which the upper and lower ends of the tunnels are independently closed, a draft-chimney having flues corresponding and connecting with the upper ends of the tunnels, independent dampers in said flues, a heating-chamber having vertical subdivisions corresponding with those of the tunnels, a heater located in each chamber, and a flue common to all the heaters connecting with the chimney or stack.

3. The combination in an evaporator of an inclined casing having parallel longitudinal channels with side cleats, and trays fitting and movable thereon, said tray series being separated by spaces gradually increasing from the top downward, and with correspondingly increasing heat-admission openings, heating-compartments located beneath the lower end with openings therefrom to the tray-compartments, substantially as described.

4. The combination in an evaporator of a series of independent parallel inclined tunnels with side cleats increasingly separated from the top downward, trays slideable in line upon the cleats to form continuous shelves and intermediate passages, said trays being disposed to form inlet-passages at the lower end, decreasing in size from the bottom toward the top, heating-chambers located beneath, said lower end passages opening therefrom into the rear of the tunnels, and heat-deflecting plates, as described.

5. The combination in an evaporator of heating-chambers, a series of independent, parallel, inclined tunnels above the chambers with side cleats and trays slideable thereon to form intermediate heat-passages increasing in width from the top downward, and disposed at the rear to admit gradually-decreasing volumes of heat from the bottom upward, and independent draft-flues connected with the discharge ends of the passages, said flues having dampers and hoods whereby the flow through the drying-passages is controllable.

6. The combination in an evaporator, of in-

dependent heating-chambers; a series of independent, parallel, inclined tunnels above and in direct communication with the chambers; side cleats in the tunnels and a series 5 of trays slideable on the cleats and separated by spaces which gradually increase from the top downward, and with corresponding heat-admission openings; a series of doors located one above another in pairs at each end of the 10 tunnels, whereby sets of trays coincident with

each set of doors may be manipulated independent of the others; and independent draft-controlling mechanism for each tunnel.

In witness whereof I have hereunto set my hand.

WILLIAM C. ANDERSON.
